UNITED STATES PATENT OFFICE.

STEPHEN C. EMMERTH, OF McADOO, PENNSYLVANIA.

SHOE-PROTECTOR.

1,205,983.

Specification of Letters Patent. Patented Nov. 28, 1916.

Application filed May 19, 1915. Serial No. 29,048.

To all whom it may concern:

Be it known that I, STEPHEN C. EMMERTH, a citizen of the United States, residing at McAdoo, in the county of Schuylkill 5 and State of Pennsylvania, have invented certain new and useful Improvements in Shoe-Protectors, of which the following is a specification.

My invention relates to improvements in 10 shoe protectors, the object of the invention being to provide a device of the character stated which may be readily positioned on the shoe, which will protect the toe and heel of the shoe from injury by reason of contact 15 with stones or other sharp cutting particles, and which will be so constructed as to permit the user to readily move about without unduly hampering him.

A further object is to provide a shoe 20 protector of the character stated in which a series of wear plates are secured to the sole and heel of the protector, the wear plates on the sole having their lines of juncture so arranged as to facilitate the bending of the 25 protector in accordance with the movement of the foot in walking.

A further object is to provide a device of the character stated which can be manufactured and sold at a reasonably low price, and 30 which will supply a great need in the mines and other places where the leather shoes are injured by the cutting action of stones and the like.

With these and other objects in view, the 35 invention consists in certain novel features of construction and combinations, and arrangements of parts as will be more fully hereinafter described and pointed out in the claim.

40 In the accompanying drawings, Figure 1 is a view in side elevation illustrating my improvements. Fig. 2 is a bottom plan view, and Fig. 3 is a view in longitudinal section through the center of the protector.

45 My improved shoe protector comprises a plate 1 which is shaped to conform to the shape of the heel and sole of the shoe 21 illustrated in dotted lines in Fig. 1. For convenience of description, I shall refer to 50 the rear end portion of the plate 1 as the heel 2, and the forward portion of the plate 1 as the sole 3.

The intermediate portion of the plate 1 constitutes the instep 4, and it will be noted 55 at the rear end of the instep that the plate

bends downwardly as shown at 5 to accommodate the heel of the shoe.

6 represents a heel guard which comprises a metal plate bent to conform to the shape of a shoe heel, and at its lower edge provided 60 with a plurality of lugs 7 bent at an angle and positioned under the heel portion 2 of plate 1, and secured by rivets 8. The forward portions of the heel guard 6 are connected by rivets 9 to a strap 10 which is 65 adapted to be passed around the shoe of the user, and secured by a buckle 11 to hold the device in place.

On the forward end of the sole portion 3 of plate 1, a toe guard 12 is located. This 70 toe guard is preferably provided with slots 13 to lighten the same and to reduce the metal to a minimum, and this toe guard at its lower edge is provided with inwardly bent lugs 14 secured to the sole portion 3 75 by rivets 8.

To the heel portion of plate 1, I secure a wear plate 15, and this wear plate conforms in shape to the shape of the heel, and is secured by rivets 8 which are utilized to secure the lugs 7. In other words, the lugs 7 are securely clamped between the heel portion 2 and wear plate 15, and the same rivets 8 are utilized for securing parts together. 80

To the sole portion 3 of plate 1, I secure 85 a plurality of wear plates 16, 17, and 18 respectively. These wear plates on their outer edges conform in shape to the shape of the sole portion 3, and they are of such shape at their transverse edges that they provide 90 lines of juncture at an angle to each other. In other words, the line of juncture between plates 17 and 18 is substantially at right angles to the longitudinal axis of the plate, while the line of juncture between the plates 16 and 17 is at an angle to the longitudinal axis of the plate. 95

As the plate will ordinarily bend upon the angles indicated by the juncture points and shape of the plates 16, 17, and 18, this 100 is a vital important point, as it renders easy the walking action. All of the wear plates 15, 16, 17, and 18 have depending flanges 19 throughout their edges, and are furthermore strengthened by intermediate flanges 20 105 which may be variously shaped. It will also be noted that in securing the toe guard 12 to the sole portion 3 of plate 1, I utilize the same rivets 8 which secure wear plate 18. In other words, the lugs 14 of top guard 12 are 110

located between the sole portion 3, and wear plate 18, and are securely clamped between said parts as well as rigidly secured by the rivets 8.

- 5 Various slight changes might be made in the general form and arrangement of parts described without departing from my invention, and hence I do not limit myself to the precise details set forth, but consider
10 myself at liberty to make such changes and alterations as fairly fall within the spirit and scope of the appended claim.

Having thus described my invention, what I claim as new and desire to secure
15 by Letters Patent is:

A shoe protector including a metallic plate

conforming to the shape of the sole of a shoe, and a plurality of wear plates secured to said metallic plate, said wear plates having transverse edges located at an angle to the longitudinal axis of the plate and having depending flanges at said transverse edges, and other depending flanges connecting said first flanges, substantially as described.

20 In testimony whereof I have signed my name to this specification in the presence of two subscribing witnesses.

STEPHEN C. EMMERTH.
